[57] CLAIM

The ornamental design for a vehicle body, as shown and described.

DESCRIPTION

FIG. 1 is a front perspective view of a vehicle body showing my new design;

FIG. 2 is a rear perspective view of the vehicle body of FIG. 1;

FIG. 3 is a side view of the vehicle body of FIG. 1; and, FIG. 4 is a front view of the vehicle body of FIG. 1, it being understood that the opposite side not shown is a substantial mirror image thereof.

It will be understood that the roof of the vehicle body is plain and unornamented, and further that the broken line showing on the tires and wheels throughout the views is for illustrative purposes only and forms no part of the claimed design.
